UNITED STATES PATENT OFFICE.

FRED W. LAKE, OF MOLINE, ILLINOIS.

MAKE-UP DEVICE FOR PRINTERS.

1,142,105.

Specification of Letters Patent.

Patented June 8, 1915.

Application filed August 7, 1913. Serial No. 783,446.

To all whom it may concern:

Be it known that I, FRED W. LAKE, a resident of Moline, in the county of Rock Island and State of Illinois, have invented certain new and useful Improvements in Make-Up Devices for Printers, of which the following is a full, clear, and exact description.

The invention relates to devices for the use of printers and more particularly for book-printing in which a number of pages are printed upon a sheet and afterward folded and trimmed. In this class of work, it is important and desirable that the type or plates for each page should be properly 15 alined and spaced relatively to the other pages printed on the same sheet, in order that each page will be correctly printed on the pages.

The present invention designs to provide 20 a make-up device which can be readily adjusted or set.

The invention also designs to provide an improved make-up guide, which, when once set by a competent printer, will enable a 25 subordinate to quickly and accurately and uniformly make up all of the forms for book in strict accordance with its adjustments, so that they will all be correctly made up.

The invention further designs to provide 30 an improved make-up device which facilitates the work and insures accurate making-up, alining and registering of the pages in a form.

The invention consists in the several novel 35 features hereinafter set forth and more particularly defined by claims at the conclusion hereof.

In the drawings: Figure 1 is a plan of a device embodying the invention. Fig. 2 is 40 a side elevation of a portion of the device on an enlarged scale. Fig. 3 is a section through the swivel connection between the gage-carrying bar and its guiding means. Fig. 4 is a detail plan, partly in section, of 45 the adjustable connection between the gage-carrying bar and one of the fingers. Fig. 5 is a section taken on line 5—5 of Fig. 4. Fig. 6 is a section through the guide-collar for the carrying-bar. Fig. 7 is a plan of 50 the connection between the bar for spacing one row of page-forms from another and the scale bar on which it is adjustably mounted. Fig. 8 is a side elevation thereof.

The make-up device is adapted to be 55 mounted on an imposing stone or table which

usually comprises a stone *a* and a surrounding frame *a'* and is removable therefrom so that the device can be separated from the table when use of the make-up device is not desired. A pair of sockets 10 are secured to 60 the frame *a'* of the table and studs 11 rigidly secured in the ends 12 of a guide-bracket 13, fit into said sockets and are provided with shoulders 14 adapted to rest upon the top thereof to rigidly, but removably, support 65 the guide-bracket 13. Ends 12 also rest upon the stone *a*. By employing these studs and sockets, the entire make-up device will be securely held against lateral movement relatively to the stone, and when the 70 studs are lifted out of the sockets, it may be separated and lifted away from the table.

A shaft 15 extends longitudinally of bracket 13 and is secured in ends 12 by screws 16. A bar 17 having a longitudinally extending channel 18 in the top thereof, also extends between and is secured in the bracket-ends 12. Shaft 15 serves as a pivotal support and guide for a gage-carrying bar 19. The pivotal connection between 80 the carrying-bar 19 and shaft 15 comprises a long collar 20 which fits around and is 85 slideable on the shaft to permit the gage-bar to be moved longitudinally of the shaft. The pivotal connection between the collar 20 and shaft 15 permits the carrying-bar to be 90 swung about the axis of shaft 15, to lift the carrying-bar above the forms so that it can be moved longitudinally. A shoe or block 95 24 is adapted to slide in the groove 18 of bar 17 and the carrying-bar 19 extends through said block or shoe. This shoe serves to truly and accurately guide the carrying-bar and to hold it squarely with respect to the bracket 12, permitting the bar 95 to be adjusted laterally with respect to the plates or type, and supports the bar so it will be close to but clear of the type or forms in the chase. A swivel connection between the collar 20 and the inner end of the carrying-bar 100 permits the carrying-bar to be rotated relatively to the collar to effect reversal of the devices carried by the bar. That is, to permit the bar to be swung 180° so that the devices on one side of the bar may be 105 shifted to the other side or reversed. This swivel-connection comprises a collar 21 secured to the inner end of bar 19 by a screw 22 and journaled in a socket 23 in collar 20. Collar 21 is removably held in said socket 110.

by a screw-collar 44 on collar 20. Bar 19 is round at 25, to permit the bar to turn in collar 44.

The chase 26 is adapted to abut against the edge of bar 17 of bracket 13. When a chase with the usual number, (16) of forms of type or plates thereon is laid in this position, the make-up device will be operative above the forms to guide the subordinate in 10 correctly making-up, alining and registering them.

At one side, the carrying-bar 19 is provided with four guide-fingers 27, each of which has one of its faces at right angles to the longitudinal straight edge of the carrying-bar to form a right angle square for accurately positioning a corresponding number of plates or pages of type. These fingers are adjustable longitudinally of the carrying-bar, so that they may be accurately set according to the size of the forms and the margins and trimming, to give the correct lateral spacing or side-margins between the pages on the sheet. After these fingers and 15 bar 31' on gage 30' have been correctly set for the pages of a form, which can be carefully done by an experienced printer, one with less skill may readily make-up, aline and register them without difficulty. Each 20 finger 27 is adjustably connected to bar 19 by a crosshead 28 which is rigid with the finger and has a rib 29 adapted to fit into the narrow portion of the T-shaped slot 30 formed in one edge of the bar 19. These 25 fingers are adapted to be locked or clamped in desired position on the bar by screws 31 having heads 32 formed to fit and slide in the inner or enlarged portion of the T-slot 30, the screws extending through head 28 30 and being provided with nuts 33 by which the heads 28 may be clamped to the carrying-bar 19, so that the fingers 27 and the edge of bar 19 will form correct right angles. By adjusting these fingers to correspond to 35 the correct places for spacing for the pages, the carrying-bar, when placed over the forms, will correctly indicate the position for each form in a row of pages. The forms, when made up according to said angles, will 40 leave the desired margin for trimming and binding, and by following the location and angle indicated by the carrying-bar and fingers, great accuracy and uniformity in making-up and alining the pages of a form will 45 be attained.

A graduated scale 30' is secured to the edge of the carrying-bar 19 opposite to that from which fingers 27 extend, and a straight edge or bar 31' is slidably mounted on the 50 scale, so that it may be adjusted to and from the carrying-bar 19. Bar 31' serves as a gage for indicating the proper top and bottom spacing between the tops of pages, or spacing between one row of pages and the 55 next, and so that the pages will be properly

spaced apart in length. Each bar 31' is adjustably secured to the scale bar 30' by a screw 33' which is adapted to clamp said bars together and against relative movement.

The operation of the improved device will 60 be as follows: A chase with a number of page-forms therein is placed against the side of bar 17 of bracket 13, so that it will be in definite relation to the bracket 13. The fingers 27 will be set in properly spaced 65 relation on the carrying-bar 19 to correspond to the correct side-spacing between the pages, and the gage-bar 31 will be set at a distance from the edge of bar 19 between the ends of said pages to the 70 correct distance between corresponding ends of two adjacent rows of pages and to leave the correct marginal spaces. The operator can slide the carrying-bar longitudinally, as a result of the sliding connection 75 between the collar 20 and shaft 15 and the sliding-connection between block 24 and the grooved bar 17, until the carrying-bar is correctly located for one row of forms or 80 pages. The fingers on bar 19 and its contiguous straight edge will constitute right-angle squares for guiding the operator in making-up, alining and registering the forms in one row. When the fingers have 85 been once adjusted to give the correct side-spacing between the pages, the operator need only follow the indications of the right-angle squares formed by the fingers and the carrying-bar 19, and in doing this, all the 90 page-forms will be accurately alined and will be correctly spaced from one another. When one side of a row of pages of a form has been thus made up, bar 19 will be lifted 95 upwardly to withdraw shoe or block 24 from groove 18 to clear the forms, and the carrying-bar can then be turned in its swivel connection with the sliding collar 20, to bring the fingers upon the opposite side of the bar and to bring the spacing-bar 31' 100 into registry with the edges of a row of plates which have been made-up. By bringing the gage-bar into registry with the edges 105 of the pages which have been made up, the right angle squares formed by the fingers 27 and bar 19 will be correctly spaced relatively to the ends of the row of made-up 110 forms to insure the proper spacing for the length of the pages or the desired top and bottom margins. This operation may be continued until all of the plates or pages in a 115 chase have been made up.

The invention thus provides a simple device for aiding and guiding the operator in making-up and alining and registering the forms and gage the depth of the same. The device in its entirety may be readily attached to the usual support upon which the chase with the form therein is laid, may be readily removed therefrom when desired and may be readily adjusted for different 120

forms. The work of making-up, alining and registering forms is greatly facilitated and great accuracy is attained, particularly by those not so well skilled in the art.

5 The invention is not to be understood as restricted to the details set forth, since these may be modified within the scope of the appended claims without departing from the spirit and scope of the invention.

10 Having thus described the invention, what I claim as new and desire to secure by Letters Patent, is:

1. In a printer's make-up device, the combination of a guide, adapted to be secured to a support, a bar slidably and pivotally mounted on the guide, and fingers forming rigid right-angle squares with the edge of the bar and extending horizontally therefrom, and adjustable longitudinally thereon 20 to indicate the correct position of a row of pages.

2. In a printer's make-up device, the combination of a guide, means for removably securing the guide to a support, a bar slidably and pivotally mounted on the guide, and fingers adjustable longitudinally along the whole length of the bar to indicate the position of a row of pages.

3. In a printer's make-up device, the combination of a guide-bracket adapted to be secured to a support, a shaft held in said bracket, a bar slidably mounted on the shaft, means between the bar and the bracket for guiding the bar longitudinally of the shaft, 35 and fingers on the bar for indicating the position of a row of pages.

4. In a printer's make-up device, the combination of a guide-bracket, means for securing it to a support, a shaft held in said bracket, a bar slidably and pivotally mounted on the shaft, means between the bar and the bracket for guiding the bar longitudinally of the shaft, and fingers on the bar for indicating the position of a row of pages.

45 5. In a printer's make-up device, the combination of a guide-bracket adapted to be secured to a support, a shaft held in said bracket, a bar slidably mounted on the shaft, means between the bar and the bracket for guiding the bar longitudinally of the shaft, and fingers extending horizontally from said bar and adjustable thereon for indicating the position of a row of pages.

60 6. In a printer's make-up device, the combination of a guide, a bar slidably mounted on the guide, adjustable fingers extending horizontally from one side of the bar for indicating the position of a row of pages, means for securing said fingers in adjusted position, and a connection for the bar which permits the fingers to be reversed from one side to the other.

65 7. In a printer's make-up device, the combination of a guide, a bar slidably and pivotally connected to the guide, adjustable

fingers extending horizontally from one side of the bar, means for securing said fingers in adjusted position, and a connection for the bar which permits the fingers to be reversed from one side to the other.

70

8. In a printer's make-up device, the combination of a guide, means whereby the guide may be secured to a support, a bar slidably and pivotally connected to the guide, fingers at one side of the bar for indicating the position of a row of pages, and a gage-bar at the other side of the slideable bar for spacing the slideable bar relatively to a row of pages.

75 9. In a printer's make-up device, the combination of a guide, a bar slidably connected to the guide, fingers adjustable on and at one side of the bar for indicating the position of a row of pages, an adjustable gage-bar at the other side of the slideable bar for spacing the slideable bar relatively to a row of pages, and a swivel connection for the slideable bar which permits it to be reversed.

80 10. In a printer's make-up device, the combination of a guide, a bar slidably connected to the guide, fingers adjustably carried by the bar for indicating the position of a row of pages, a scale-bar on said first bar, and an adjustable gage-bar on the scale-bar for spacing the slideable bar relatively 90 to a row of pages.

85 11. In a printer's make-up device, the combination of a guide, a bar slidably and pivotally connected to the guide, fingers adjustably carried by the bar for indicating the position of a row of pages, a scale-bar on said first bar, and an adjustable gage-bar on the scale-bar for spacing the slideable bar relatively to a row of pages.

95 12. In a printer's make-up device, the combination of a guide, means for securing the guide to a support, a bar slidably and pivotally connected to the guide, fingers on one side of the bar for indicating the position of a row of pages, a scale-bar projecting from the other side of said bar, a gage-bar on the scale-bar for spacing the slideable bar relatively to a row of pages, and a swivel connection for the slideable bar which permits its reversal.

105 13. In a printer's make-up device, the combination of a guide-bracket, means for removably securing it to a support, comprising studs and sockets, a bar slidably and pivotally connected to said bracket, fingers at one side of the bar for indicating the position of a row of pages, an adjustable gage-bar at the other side of the slideable bar for positioning the slideable bar relatively to a row of pages and a scale-bar upon which 110 the gage-bar is mounted.

120 14. In a printer's make-up device, the combination of a guide-bracket having a grooved guide, means for detachably securing said bracket to a support, a shaft held 125

115

120

125

130

in said bracket, a bar slidably mounted on the shaft, means on the bar adapted to engage the grooved-guide for guiding the bar longitudinally of the shaft, and fingers on the bar for indicating the position of a row of pages.

15. In a printer's make-up device, the combination of a guide-bracket, a shaft held in said bracket, a collar slidably and rotatably mounted on the shaft, a bar, a collar on the bar and means for pivotally connecting the collar on the shaft and the collar on the bar to form a swivel connection, and fingers on the bar for indicating the position of a row of pages.

16. In a printer's make-up device, the combination of a guide-bracket, of a shaft held in said bracket, a collar slidably and rotatably mounted on the shaft and provided with a socket, a bar, a collar on the bar fitting into said socket, means for rotatably securing the collar on the bar in said socket on the slideable collar and fingers on the bar for indicating the position of a row of pages.

17. In a printer's make-up device, the

combination of a guide, means whereby the guide may be adjustably secured to a support, the bar having a groove extending lengthwise thereof, said bar being slidably connected to the guide, fingers on one side of the bar for indicating the position of a row of pages and means fitting the groove of the bar and connected to the fingers for adjustably securing the fingers on the bar.

18. In a printer's make-up device, the combination of a guide, means whereby the guide may be adjustably secured to a support, a bar having a slotted groove extending lengthwise thereof, said bar being slidably connected to the guide, fingers at one side of the bar for indicating the position of a row of pages and means fitting the groove and extending through the slot thereof passing through the fingers, and adjustable means for securing the means to secure the fingers on the bar.

FRED W. LAKE.
